I claim the ornamental design for a toilet, as shown and described.

CLAIM

I claim the ornamental design for a toilet, as shown and described.

FIG. 1 is a perspective view of an embodiment of the claimed design;

FIG. 2 is a front view of the claimed design shown in FIG. 1;

FIG. 3 is a rear view of the claimed design shown in FIG. 1;

FIG. 4 is a top view of the claimed design shown in FIG. 1; FIG. 5 is a bottom view of the claimed design shown in FIG. 1;

FIG. 6 is a side view of the claimed design shown in FIG. 1; and,

FIG. 7 is another side view of the claimed design shown in FIG. 1.

In the drawings, the broken lines depict portions of the toilet that form no part of the claimed design.
